Primary Examiner — Lauren R Calve(74) Attorney, Agent, or Firm — Richard G. Topolewski(57) CLAIM

The ornamental design for a handbag hanger, as shown and described.

DESCRIPTION

FIG. 1 is a front perspective view of a handbag hanger being used on a rod holding a handbag showing my new design;
 FIG. 2 is a back perspective view thereof;
 FIG. 3 is a second back perspective view thereof;
 FIG. 4 is a front perspective view thereof;
 FIG. 5 is a front view thereof;
 FIG. 6 is a back view thereof;
 FIG. 7 is a right view thereof;
 FIG. 8 is a left view thereof;
 FIG. 9 is a top view thereof; and,
 FIG. 10 is a bottom view thereof.

The broken line showing of a hanging rod and handbag depicts the environment and forms no part of the claimed design. All other broken lines depict portions of the handbag hanger that form no part of the claimed design.
